Filed Feb. 26, 1959, Ser. No. 795,803

2 Claims. (Cl. 308—6)

This invention relates to bearing-retainer indexing means for antifriction die sets. More particularly, it relates to indexing means for the relatively axially movable bearing retainer, guide post, and guide bushing of the die sets of punch presses and other reciprocating machine tools.

The present invention is an improvement over the structure disclosed in the patent to Blazek et al. No. 2,846,278 which issued August 5, 1958, and especially over the structure disclosed in FIGURE 7 of such patent.

The present invention aims primarily to provide position-maintaining means for the movable bearing retainers of antifriction die set guiding and aligning devices. Such devices are formed customarily so that a punch-carrying movable holder of a die set is provided with guide posts which are axially receivable for relative longitudinal movement in longitudinal holes or bores of stationary bushings carried by a complementary die holder of the set. In association with these parts, tubular ball-bearing retainers of the movable "floating" type are arranged and held so that ball elements carried thereby are disposed in annular receiving spaces provided between the outer wall surfaces of the posts and the adjacent inner wall surfaces of the bushing bores, the ball elements being disposed in simultaneous contact with post and bushing surfaces.

This construction is such as to provide for accurately guided and confined reciprocatory movement on the part of the die and punch-supporting holders of a die set. The construction eliminates undesired lateral motion between parts and enables the punch and die members of the set to be brought into and out of true forming contact with work pieces positioned between the same in the press. Such alignment of the relatively movable die and punch members is made possible through the use of said ball element guide devices, and results in prolonging the working life of the punch and die members, as well as enabling the same to produce more rapidly and accurately forming operations on work pieces. Such pressure-loaded ball-bearing guiding devices for die sets are disclosed, for example, in the prior patent to Conner No. 2,422,774 granted June 24, 1947.

In this type of die set guide apparatus, upon the movement of the posts into the adjacent ends of the bushing bores, the outer cylindrical surfaces of the posts engage the ball elements of the retainers and force the same against the complementary inner cylindrical walls of the associated bushing bores. Since the diameter of each ball element of the bearing retainers is such that it exceeds slightly the width of the annular spaces which the retainers occupy, each ball element so positioned is placed under compression by its confined engagement with adjoining post and bushing surfaces. Such "loaded" or pressure engagement of the ball elements causes the retainers to move linearly with the associated movable posts but at a relatively reduced or lower rate of travel. It is important, therefore, in the proper functioning of each guide that the floating bearing-retainers move at a controlled rate concomitantly with the posts in providing antifriction guidance, whereby to minimize wear and maintain positive alignment between the relatively movable die set parts.

Because of the "floating" characteristics of the ball-bearing retainers, that is, the absence of any direct physi-

2

cal connection between the retainers and associated posts and bushings, it has been somewhat difficult for machinists to so assemble each guide and dispose the retainers so that the bearing elements thereof will maintain their pre-loaded positions throughout full back and forth stroke movements of the guide assembly. If, for example, a retainer should fail to move with its reciprocatory posts, excessive friction, part wear and looseness would develop rapidly and impairment and loss of guiding function of the guide assembly would take place.

According to said Patent No. 2,846,278, there was provided positioning means for use in association with such antifriction guide appliances for die sets, whereby in assembling the parts thereof it was necessary to arrange the parts of the guide assembly in their proper or required relative order in the resulting assembly. Furthermore, this positioning means maintained the retainers properly interposed between the posts and bushings in all their working positions and served during active cooperation thereof to preclude movement on the part of said retainers to positions in which all the antifriction bearing elements positioned therein would be removed from simultaneous pressure engagement of associated posts and bushings.

The present invention relates particularly to a structure in which the guide bushings are disposed on the upper die holder and the guide posts are located on the lower die holder with the posts and bushings movable relative vertically during the working stroke of the die members, as disclosed in FIGURE 7 of said Patent No. 2,846,278. However, the indexing and retaining means of this present invention is an improvement over the means for floatingly suspending the retainer in an initial predetermined position from the associated bushing of each antifriction guide assembly.

Additional objects, advantages, structural and operational features will be apparent from the following description and the drawing which disclose the preferred embodiment of this invention.

In the drawing:

FIGURE 1 is a schematic side elevational view showing antifriction guide assemblies for machine press die sets in which this invention is embodied.

FIGURE 2 is a vertical or axial sectional view taken along line 2—2 of FIGURE 1 through one of the guide assemblies.

FIGURE 3 is a horizontal or transverse sectional view taken along line 3—3 of FIGURE 2.

With reference to the drawing, relatively movable die holders 10 and 11 of a die set are shown and are provided with one or more antifriction guide assemblies 12, two being shown as an example. The assemblies 12 are employed for maintaining the holders 10 and 11, and parts carried thereby, in proper alignment or position of relative registry during working movements of a punch press, or other machine tool, on which such a die set is mounted.

Each assembly 12, according to this invention, comprises a cylindrical bushing 13 rigidly carried by and depending from an opening formed in the die holder 10 of the die set. The bushing provides an internal cylindrical bore 14 of uniform diameter throughout its length and the bore has machined, ground, hardened and/or polished wall surfaces held to close dimensional tolerances. The die holder 11 carries for each assembly 12 a fixed, rigid, upstanding pin or post 15 having cylindrical outer wall surfaces of uniform diameter substantially throughout the length thereof, these surfaces being held within close dimensional limits by machining and otherwise finishing and hardening the same to a true cylindrical contour. The member 19 is illustrated as a downwardly movable member and the member 11 is illustrated as a stationary member but this relationship may be reversed or, in fact, both

members may be movable since it is the relative movement that is important.

Mounted for axial movement in each guide assembly is a tubular, sleeve-like, bearing retainer 16. Each retainer 16 is formed with a plurality of transverse relatively spaced openings 17 constituting sockets for the rotatable retention of a plurality of ball-bearing elements 18, these openings being shown arranged in vertically spaced horizontal rows but other arrangements are possible. The wall thickness of each retainer 16 is less than the radial width of an annular space 19 formed between each interfitting set of guide bushings 13 and posts 15 (FIGURE 3) when they are disposed in relatively telescoped relationship. Each bearing element 18, however, possesses a diameter slightly greater than the radial width of the space 19 receiving the same. This enlarged diameter is important in the operation of a guide assembly of this nature, in that when a bushing 13 and a post 15 move axially into telescoping relationship and an associated retainer 16 simultaneously moves axially therebetween, the ball-bearing elements will be crowded between the post 15 and the bushing 13 to place the engaged ball elements 18 under compressive forces. The ball elements 18 so engaged are rotated, with the result that the retainer 16 moves axially concomitantly with the relatively moving post 15 and the bushing 13 but at a lower rate of linear travel. Such relative axial motion of the post 15, the bushing 13, and the retainer 16, is continued as the ball elements 18 are progressively engaged between the post and bushing producing a positive guiding action wherein lateral motion is eliminated and accuracy thereby obtained in punch and die registry.

According to the present invention, there is provided the indexing and positioning means illustrated best in FIGURES 2 and 3. This means will serve to position the retainer and the bushing in predetermined relationship and in the example illustrated it floatingly suspends the retainer 16 from the vertically movable bushing 13, with about one-half its axial extent telescoped upwardly within the lower end of the bushing and its other half depending from the bushing, at the time the post 15 and the bushing 13 are out of operative relationship prior to the beginning of the working stroke of the press, as shown in FIGURE 2. However, other indexed relative positions are possible. This means comprises means for splining the retainer to the bushing and includes a grooved keyway or slot 25 which is formed in the inner surface of the bore 14 of the bushing 13 and extends the full length thereof being open at each end at the corresponding extremity of the bushing. For cooperating with this keyway slot 25, a key is provided and may be in the form of a suitable stop device but is shown as a stud 26 which is fixed in an opening 27 adjacent the upper end of the retainer 16 and extends radially outwardly into the slot 25 with clearance between its outer end and the bottom of the slot. Also, as indicated in Figure 3, clearance is provided at the sides of the stud and the adjacent sides of the slot by having the stud of less diameter than the slot. To limit downward movement or dropping of the retainer 16 out of the bushing 13, an abutment of suitable form is provided and is shown as a stop pin or stud 28 in the keyway slot 25 at a suitable location. This stud 28 is fixed in an opening 29 in the bushing 13 which communicates with the slot 25 and the stud 28 extends radially inwardly into the groove but terminates short of the inner surface of the bore 14. As the retainer 16 is moved downwardly in the bushing 13 by gravity, the stud 26 will engage the stud 28 and floatingly suspend the retainer from the lower end of the bushing 13. However, the retainer will be so suspended that it can be moved upwardly within the bushing 13.

In the initial assembling of the retainer 16 within the bushing 13, in the example shown, the stud 28 will be located to suspend the retainer 16 with about half its length depending from the bushing 13 and its other half telescoping upwardly therein. However, one or more

additional openings 29a may be provided in the bushing 13 to position the stud 28 at a different location along the bushing and one or more additional openings 27a may be provided in the retainer 16 to position the stud 26 at a different location, to index the bushing 13 and post 15 as desired. The retainer 16 can be dropped within the bushing 13 until the stud 26 carried thereby engages the stop pin 28 carried by the bushing 13. This relationship will be maintained until the die or punch holder 10 moves downwardly sufficiently to cause the post 15 of each assembly 12 to telescope within the lower end of the bushing of that assembly. Continued downward movement of the bushing 13 in the working stroke of the press, in the example shown, will cause the bushing 13 and the post 15 to telescope beyond the relative position shown in FIGURE 2 and the balls 18 of the retainer which are therebetween will be positively rotated and placed under compression by the relatively axially moving bushing and post.

The positive rotation thus imparted to the compressively loaded ball elements 18 causes the retainer 16 to descend with the bushing 13 and move downwardly along the post 15 but at a lower rate of travel, which will, in fact, be substantially one-half the rate of the downward movement of the bushing 13 over the post 15. During upward movement of the bushing 13, a reverse action will take place until the position shown in FIGURE 2 is reached at which time, the retainer 16 will again be floatingly suspended from the bushing 13 by means of engagement of the pin 28 with the pin 27.

Through the use of the indexing and positioning means described, the vertically movable ball-bearing-carrying retainer or sleeve member 16 of an antifriction die set guide assembly is supported or retained against downward movement in a predetermined position relative to the associated movable bushing 13 and stationary post 15 of the guide assembly. Furthermore, the construction of the positioning means of the present invention is such that the retainer-supporting function of the bushing 13 is released or removed automatically with the descent of the bushing on its working stroke, so that the retainer 16 will be caused positively to move linearly with the associated movable bushing at a controlled relative rate of travel throughout the full working stroke of the movable die holder 10. When the latter returns to its normal or starting position and returns the bushing 13 to such position, the retainer member 16 returns with it and occupies a predetermined position relative thereto. At this time, the ball elements 18 of the retainer member 16 are relieved of the compressive forces resulting from their simultaneous contact with contiguous surfaces of the movable and stationary guide members 13 and 15, respectively, of the assembly 12. The telescopic relation between the guide members 13 and 15 during a working stroke and the interposition of the retainer member 16 with its ball elements 18, enables the retainer member 16 to be movably positioned in its established relation with said guide members. The retainer 16, it will be observed, moves in unison with the associated bushing 13 when the bearing elements 18 are unloaded, but when said elements are loaded or pressure confined between the post 15 and the bushing 13, the bushing-carried retainer holding or indexing means is released to admit of independent relative movement of the retainer 16 with respect to the bushing 13.

The indexing means is extremely simple and inexpensive though very effective in the manner indicated above. Since the keyway or slot 25 extends the full length of the bushing 13, it may be formed therein by simple and inexpensive operations. Furthermore, the stop members or devices 26 and 28 provide simple but positive stop means for suspending the retainer 16 in a predetermined position relative to the bushing 13. It is simple to locate the stop members 26 and 28 in predetermined fixed locations on the respective members 13 and 16 and to then merely drop the retainer 16 into the bushing 13 and to thereby positively locate the retainer and the bushing by engage-

ment of the stop 26 with the stop 28. Furthermore, as pointed out above, the positions of these stops may be varied as desired to selectively position the bushing 13 and the retainer 16.

According to the provisions of the patent statutes, the principles of this invention have been explained and have been illustrated and described in what is now considered to represent the best embodiment. However, it is to be understood that, within the scope of the appended claims, the invention may be practiced otherwise than as specifically illustrated and described.

Having thus described this invention, what is claimed is:

1. In a die set; upper and lower die-supporting members relatively movable toward and from one another; a tubular bushing carried by the upper of said members and having an inner surface formed with a longitudinally disposed groove; a guide pin carried by the lower of said members in telescoping, axial alignment with said bushing; a ball-bearing retainer positioned between said pin and bushing; a stop device carried by and projecting outwardly from said retainer and into the groove of said bushing, said stop device being slidable longitudinally within the groove of said bushing; and abutment means carried by said bushing and engageable with said stop device for indexing said retainer in a preselected position with respect to said bushing, said stop device being adjustable to different, axially spaced positions on said retainer so as to

vary the indexed position of said retainer with respect to said bushing.

2. In a die set; upper and lower die-supporting members relatively movable toward and from one another; a tubular bushing carried by and depending from the upper of said members and having an inner wall surface formed with a longitudinally extending key way; a guide pin carried by and projecting upwardly from the lower of said members in telescoping, axial alignment with said bushing; a ball-bearing retainer movably carried between said pin and bushing; and a pair of relatively engageable stop devices carried respectively by said bushing and said retainer and extending into the key way of said bushing and operable upon relative engagement to maintain said retainer in a preselected position relative to said bushing and to preclude withdrawal of said retainer from the lower end of said bushing, said stop devices being relatively adjustable longitudinally of said key way to vary the preselected position between said bushing and said retainer.
